UNITED STATES PATENT OFFICE.

LEO KERN, OF VILLINGEN IN BADEN, GERMANY, ASSIGNOR TO KIENZLE UHREN-FABRIKEN AKTIENGESELLSCHAFT, OF SCHWENNINGEN A. NECKAR, GERMANY, A CORPORATION OF GERMANY.

FARE INDICATOR.

Application filed January 13, 1927, Serial No. 160,842, and in Germany January 15, 1926.

My invention relates to improvements in fare indicators, and more particularly in fare indicators of the type in which, in addition to the mechanism for indicating the charges made in accordance with the length of the way and with the time the cab has been waiting, registering mechanism is provided for indicating the totals of the said charges. In order to permit the separate registration of the total of the charge made for the time the cab has been waiting, it has been proposed to provide separate registering mechanism for the said total, which separate registering mechanism is thrown into operation by rocking the tax drum connected with the usual flag into a special position for recording the charge for the time the cab has been waiting. If in apparatus of this class the driver does not set the tax drum in the proper position the time of waiting is not recorded. Therefore, in order to be independent of the driver setting the tax drum, it has been proposed to provide frictional coupling members for throwing the registering mechanism for the charges made for the time the cab has been waiting into and out of operation when the cab begins or ends a drive. However, it has been found difficult to throw the said registering mechanism into and out of operation by means of the said frictional coupling members.

The object of the improvements is to provide a fare indicator of the class referred to, in which the said objections are obviated, and with this object in view my invention consists in connecting the said registering mechanism recording the charge for the time the cab has been waiting with the clock work as well as with the mechanism indicating the fares for the drives, the last-named mechanism being connected with the registering mechanism so as to move the pawl of the pawl and ratchet mechanism in the reverse direction in which no values are transmitted thereto. Thus, the said registering mechanism is operated by the clock work only when the driving mechanism operated by the movement of the vehicle has a velocity smaller than that of the clock operated mechanism. In this construction the registering mechanism indicating the charge made for the time the cab has been waiting operates independently of the tax

drum. Further, frictional coupling members are not needed. 55

For the purpose of explaining the invention an example embodying the same has been shown in the accompanying drawing in which the same letters of reference have 60 been used in all the views to indicate corresponding parts. In said drawing,

Fig. 1, is a top plan view of the mechanism,

Figs. 2 and 3, are sectional elevations 65 taken respectively on the lines 2-2 and 3-3 of Fig. 1,

Fig. 4, is a sectional plan view of a part of Fig. 1,

Fig. 5, is a detail sectional elevation taken 70 on the line 5-5 of Fig. 1,

Fig. 6, is a top plan view of Fig. 5,

Fig. 7, is a sectional elevation taken on the line 7-7 of Fig. 1, and Fig. 8 is a diagrammatic sectional elevation on the line 75 8-8 of Fig. 1.

In the example shown in the drawing the fare indicator comprises a worm shaft 1 adapted to be rotated from a rotary part of the vehicle and connected with gear wheels 3 and 4 through the intermediary of a worm gearing 2. The gear wheel 4 is connected with a cam wheel 6 by means of a pawl and ratchet mechanism 5, and the said cam wheel is connected with the indicating mechanism 80 and registering mechanism for the fare charged for the drives. The clock work is connected with a gear wheel 7, and the said gear wheel is likewise connected with the cam wheel 6 by means of a gear wheel 8 85 and a pawl and ratchet mechanism 9. Thus the clock work operates the cam wheel 6 when the cab stops or its velocity is so small that the clock work drives the cam wheel 6 at a higher velocity than the gear wheel 4. 90 95

For registering the total of the charges recorded by means of the clock work and made for the time the cab has been waiting, a registering mechanism 11 is provided, which is adapted to be operated by means of pawl and ratchet mechanism, as is known in the art. For driving the said registering mechanism 11 a differential gearing 10 is provided which includes bevel gears 15 and 17 loosely mounted on a shaft 18 and a gear wheel 16 meshing with the bevel gears 15 and 17 and rotatably mounted on an arm 21 fixed to the shaft 18. The gear wheel 15

is fixed to a gear wheel 19 meshing with the gear wheel 3, and the bevel gear 17 is connected with a gear wheel 20 meshing with the gear wheel 8. The shaft 18 is connected with the pawl and ratchet mechanism forming a part of the registering mechanism 11 by means of gear wheels 12, 13 and 14.

The operation of the apparatus is as follows:

The cam 6 is adapted to be operated either from the worm gearing 2 connected with one of the wheels of the vehicle, or from the gear wheel 7 which, as shown in Fig. 2, may be of two diameters, the part of smaller size being connected with the clock work. The operation of the said cam is known in the art, and I deem it unnecessary to describe the same in detail. From the gear wheel 3 rotary movement is transmitted through the intermediary of the gear wheel 19 to the bevel gear 15, by means of which the gear wheel 16 and the arm 21 are made to revolve thus imparting rotary movement to the shaft 18, which rotary movement is transmitted through the gear wheels 12, 13 and 14 to the pawl and ratchet mechanism connected with the registering mechanism 11. The direction of the rotary movement thus imparted to the shaft 18 is such that no movement is imparted by the said pawl and ratchet mechanism to the registering mechanism 11, so that the numeral wheels 22 are not advanced. If the cab stops, the indication of the fare is made by the clock work, the rotary movement of the gear wheel 8 being transmitted through the gear wheel 20 to the bevel gearing 17. By the said bevel gearing the shaft 18 is rotated in a direction opposite to that imparted to the shaft by means of the gear wheel 19. Therefore

the rotary movement imparted to the shaft 18 from the clock mechanism is transmitted to the registering mechanism 11 in a direction for advancing the numeral wheels 22.

45

While in describing the invention reference has been made to a particular example embodying the same I wish it to be understood that my invention is not limited to the construction shown in the drawing, and that various changes may be made in the general arrangement of the apparatus and the construction of its parts without departing from the invention.

50

I claim:

55

1. In a fare indicator, the combination, with driving mechanism controlled by the moving vehicle, driving mechanism controlled by the clock work, and registering mechanism including an operating member adapted to transmit movement to the registering mechanism in one direction and to run idle when operated in the opposite direction, and means intermediate said driving mechanisms and operating member for moving the same respectively in opposite directions.

60

2. In a fare indicator, the combination, with driving mechanism controlled by the moving vehicle, driving mechanism controlled by the clock work, and registering mechanism including an operating member adapted to transmit movement to the registering mechanism in one direction and to run idle when operated in the opposite direction, and a differential gearing intermediate said driving mechanisms and operating member and adapted to transmit rotary movement for said driving mechanisms to said operating member respectively in opposite directions.

70

In testimony whereof, I hereunto affix my signature.

LEO KERN.
